UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

METHOD OF ASSEMBLING PARTS OF BOOTS AND SHOES.

1,076,620.

Specification of Letters Patent.

Patented Oct. 21, 1913.

Original application filed August 15, 1906, Serial No. 330,705. Divided and this application filed October 26, 1907. Serial No. 399,316.

To all whom it may concern:

Be it known that I, ORRELL ASHTON, a citizen of the United States, residing at Lawrence, in the county of Essex and Commonwealth of Massachusetts, have invented certain Improvements in Methods of Assembling Parts of Boots and Shoes, of which the following description, in connection with the accompanying drawings, is a specification, like reference characters on the drawings indicating like parts in the several figures.

This invention relates to methods of assembling parts of boots and shoes.

It is a common practice to prepare the parts of a boot or shoe for the pulling-over and lasting operations by bringing them together and securing them at the heel. The present invention contemplates a novel procedure for performing this assembling operation in an efficient manner. The procedure is preferably carried out by the aid of mechanism such as is hereinafter described, but it will be understood that it may be practised with the aid of other mechanism and that the several steps hereinafter mentioned may, if desired, be performed by hand.

As is well-known, the parts brought together in the assembling operation commonly comprise a lined upper, a counter and an innersole. In assembling these parts, the counter is inserted beneath the lining of the upper at the heel, the last is placed within the upper and the innersole is placed upon the bottom of the last, and the upper and counter then secured to the innersole by a tack driven through the upper, the counter and the innersole at the extreme rear of the heel. It is particularly important in the assembling operation that the counter be brought into close relation to the end edge of the innersole before the parts are secured together. An improper position of the assembled counter is ordinarily not remedied during the following operations, so that a shoe which has been thus improperly assembled is impaired in value. An important feature of the procedure hereinbefore described accordingly consists in pressing the counter not only down upon the face of the innersole, preferably sustained upon

a last, but also against the rear edge of the innersole and the rear face of the last before securing it to said innersole. In pressing the counter against the rear face of the last or down upon the face of the innersole, there is ordinarily a tendency to spread the ends of the counter and move them down below the side edges of the innersole toward the cone of the last. This displacement is objectionable more particularly in that it imposes upon the last the necessity of raising the ends of the counter into position above the innersole before lasting. According to the present procedure, the ends of the counter are held from downward movement past the side edges of the innersole while the counter is being pressed into proper relation to the innersole and secured thereto.

In the manufacture of some kinds of shoes, particularly in the better grades known as welt shoes, it is desirable to secure the parts of the shoe to the rear face of the last. An important object of this operation is to prevent lateral displacement of the seam at the rear of the shoe during the pulling-over operation. According to the present procedure, a fastening is driven through the upper, counter and lining into the rear face of the last before the counter is secured to the innersole. This fastening is inserted after the counter has been pressed down upon the bottom of the last and before it is pressed against the rear edge of the innersole. After said fastening has been inserted, the upper is strained over the rear edge of the innersole and secured to the innersole. The upper between the two fastenings is thus brought closely against the rear face of the last.

Other features of the invention will be described in the following description.

In the drawings, which illustrate a machine by the aid of which the present method may be conveniently practised,—Figure 1 is a view in side elevation of the more important parts of the machine; Fig. 2 is a view in horizontal section on the line $x-x$ of Fig. 1; Fig. 3 is a view in vertical section showing parts of the machine immediately adjacent to the last operated upon; Fig. 4 shows a shoe after being as-

sembled, and Fig. 5 shows a shoe provided with a straight counter before the completion of the assembling operation.

Referring to the drawings, the reference numeral 3 indicates a suitably journaled shaft arranged to be given one complete rotation at the will of the operator by the actuation of a treadle rod 15. Below the shaft 3 the frame of the machine is provided with a horizontal table 21 in which is formed a groove adapted to receive a stem 22, the forward end of said stem constituting a rest 24 arranged to be engaged by the heel end of a shoe. A stop 26 is mounted upon the frame 10 in advance of the rest 24 in position to bear on the sole of the shoe, the lower face of said stop being corrugated and the stop being arranged for vertical adjustment. A horizontal guideway 28 is formed upon the frame 15 below the rest 24 and the stop 26, and a post 30 is mounted to slide upon this guideway. A vertically adjustable sleeve 32 is arranged within the post 30, said sleeve supporting a rod 36 constituting a last supporter. The 20 adjustment permitted the sleeve 32 allows the position of the upper end of the last supporter to be varied to accommodate different heights of lasts. The last supporter 36 is engaged by a lever 42 which is forced upwardly by an adjustable coiled spring 46, the last supporter being thus yieldingly sustained to provide for slight variations in height of the last. The pressure with which the innersole is clamped upon the last is 25 controlled by the spring 46. A rod 54 is arranged to be actuated by a cam upon the shaft 3, this rod bearing at its lower end yieldingly upon the lever 42. The rod 54 is normally in a depressed position in which 30 the lever 42 is held down, and when the rod 54 is automatically raised spring 46 raises the last supporter pressing the sole of the shoe against the stop 26. The vertical adjustment permitted the 35 stop 26 allows the height at which the last is held to be varied. Two levers 74 are pivoted upon the table 21 at opposite sides of the stem 22. The forward ends of the levers 74, carrying the work-engaging members 82, are 40 moved against the sides of the work by a spring 78, said members 82 being arranged to engage the upper upon opposite sides adjacent to the ends of the counter. The rear ends of the levers 74 are engaged by a lever 50 45 55 60 65 70 75 80 85 90 95 100 105 110 115 120 125 130 86, said lever 86 being actuated by a cam upon the shaft 3. When the lever 86 is moved rearwardly, it will be seen that the work-engaging members 82 are independently and yieldingly held against the work by the spring 78.

The carrier 62 for devices to be described is pivoted at 63 upon the frame and is automatically oscillated by a cam upon the shaft 3, the lower end of the carrier in its forward movement moving downward in a curved

path longitudinally of the last. A rigid presser 66 is mounted at the lower end of the carrier 62, so that it may be adjusted forwardly or rearwardly upon said carrier, and the face of the presser is arranged at an inclination, so that when it engages the shoe it conforms approximately to the angle of the last at the rear of the sole. A wiper 68 is pivotally mounted upon the carrier 62 above the presser 66, a spring 72 pressing said wiper downwardly. The wiper has its forward end curved upwardly to ride over the work more easily, and its forward edge is concave or crescent-shaped. It frequently happens that the rear seam of an upper does not extend quite to the heel seat edge of the upper so that a slit is left in its edge at the extreme rear. The crescent shape of the wiper 68 is of advantage in preventing the tack-driving mechanism hereinafter described from driving a tack through this slit and consequently failing to secure the upper to the innersole. The wiper in moving over the work tends to gather toward the longitudinal central line of the last the portion of upper acted upon.

A casing 90 is mounted upon the carrier 62, said casing inclosing a driver bar actuated by a lever 98 pivoted upon the frame and automatically rocked by a cam upon the shaft 3 coöperating with a spring arranged to depress the forward end of the lever. A tack strip is intermittently fed through a passage in the casing 90 by any suitable mechanism, and the lower end of the casing 100 90 is in line with an orifice in the wiper 68 through which the tack is driven through the wiped-over upper, the counter and the innersole, and is clenched upon the heel plate of the last.

The stem 22 is provided with a longitudinally arranged driver passage terminating in the rest 24 and the driver bar 108 is arranged to work in said passage and to drive a tack part way into the rear of the shoe at a point adjacent to the cone of the last. The rest 24 and the driving mechanism operating therein are vertically adjustable in order to vary the position of the tack thus driven into the rear face of the last. This vertical adjustment of the stem 22 permits the end tack to be driven, if desired, closely adjacent to the cone of the last whatever variation there may be in the height of the last or the shoes being assembled.

In some classes of work, more particularly in making Oxford shoes and especially in oxfords in which the upper is quite thin and flexible, it is desirable that the tack driven through the upper and the counter into the end of the last be inserted at a point closely adjacent to the cone of the last, in order effectually to prevent displacement of the rear seam during the pulling-over operation. As will be obvious, the end tack co-

operates with that driven through upper and counter into the innersole to hold securely from displacement the portion of the upper lying between them, and by placing the end tack as close to the cone of the last as possible, the rear seam is effectually held from displacement.

The arrangement of the parts is preferably such that the tack driven by the driver bar 198 is either perpendicular to the surface in which it is driven or is inclined toward the sole of the last. Accordingly in the construction shewn the stem 22 and its driver passage are inclined upwardly and forwardly. The feature of driving the tack obliquely toward the sole of the last is of advantage in that the tendency to upward movement of the upper produced by the wiper in moving over the edge of the last tends to draw the upper closely against the last in the vicinity of a tack thus inserted in the end of the last. It will be obvious from Fig. 3 that, if the tack were otherwise arranged this effect might not be secured,

for example, if the tack were inclined in the reverse direction *i. e.* toward the cone of the last the upward movement of the upper would tend to cause it to be moved away from the last end in the vicinity of the tack.

The driver bar 198 is reciprocated by a lever 110 pivoted upon the arm and actuated by a cam upon the shaft 3 and an adjustable coded spring arranged to move forwardly the lower end of the lever 110. A tack strip is intermittently fed through a conduit 121 at the forward end of the stem 22, said tack strip being advanced by any suitable means.

In the practice of the present method and preparatory to use of the machine shown above described the parts of the boot or shoe to be assembled are arranged upon a last. It will be understood that the manner of arranging said parts may vary according to the grade of work or other circumstances. In some grades of work, particularly in making soft shoes, the innersole is commonly tacked to the last bottom prior to assembling. Where other grades such as McKay shoes are made, the innersole is commonly loosely sustained upon the last bottom throughout the assembling operation. In bringing the parts of the boot or shoe together, the counter is inserted by hand in position within the upper, for example between the upper and its lining, the last is placed inside the upper and in the event that the innersole has not been before tacked to the last bottom, it is placed loosely upon said last bottom. Where a molded counter is employed the flange of the counter lies above the face of the innersole as shown in Fig. 4. In case a straight or unmolded counter is used, such as that shown in Fig. 5, in placing it within the upper it is positioned so that when the upper is

placed upon the last the edge of the counter will project above the edge of the innersole, this upwardly projecting portion being subsequently bent or wiped down upon the innersole. It will be understood that the straight counters are in temper when used, so that they may readily conform to the shape of the end of the last, and so that their upper edges may be bent over as stated. It is a common practice to secure a straight counter throughout its length to the upper lining by means of adhesive material, when said counter is placed within the upper. As will be obvious this insures that the counter will remain in the position which is given it within the upper. The parts of a boot or shoe having been brought together upon a last, the last is placed upon the heel pin of the machine shown, and may be then moved by hand rearwardly against the rest 24. The counter and upper are thus brought into close relation to the rear face of the last. If desired, the subsequent vertical movement of the heel pin may be depended upon to raise the work against the stop 26. It is preferred ordinarily, however, to hold the work manually against the stop 26 and rest 24 before the machine is started, since thereby the position of the work with relation to the remaining work-engaging devices may be manually controlled. This is of advantage in securing an accurate location of the work with relation to said devices before they engage the work. The heel pin ordinarily does not fit accurately the pin hole of the last, and hence a slight longitudinal or lateral tilting movement of the last upon the heel pin is commonly possible. By positioning the last initially by hand, liability of the last assuming an improper position with relation to the work-engaging devices is prevented. It may be found desirable to hold the last against the stop and rest with its bottom slightly inclined downwardly and rearwardly, in order to present the last to the wiper and presser in the most advantageous position. The last having been placed upon the heel pin in the manner desired, the machine is started by the depression of the treadle. The movement of the main shaft 3 first raises the heel pin upwardly, and if the last has not been initially brought against the stop 26, it is moved vertically by said heel pin between the work-engaging members 82, until the sole strikes the stop 26, the work remaining in contact with the rest 24 in its vertical movement and being raised into a predetermined position by the heel pin. If the last has been initially brought against the stop 26, the heel pin is merely moved vertically in the last pin hole. In either case the heel pin finally holds the last yieldingly against the stop 26.

In the further movement of the main shaft the work-engaging members 82 are

10 moved automatically against the upper at points adjacent to the ends or corners of the counter. The ends of the counter are thus held against the sides of the last, and are held against the last and the side edges of the innersole until the parts are secured together. Where the innersole is not secured to the last bottom, the members 82 have also a tendency to position the innersole 15 exactly of said last bottom.

16 While the counter is held at the corners, the carrier 62 moves forwardly longitudinally of the last, bringing the wiper 66 and presser 68 successively into engagement with the work. The wiper bends over the upwardly projecting edge of the upper at the heel, presses it down upon the innersole and tends to draw the upper into closer proximity to the last at the rear. When a straight counter is used the wiper also bends over the edge of the counter at the rear of the last, and presses it upon the innersole. In the use of a flanged counter the wiper presses the flange upon the last heel, and thus positions the counter with respect to the height of the last. When the latter engages the upwardly projecting portion of the upper or counter, said edge is permitted to catch readily upon the edge of the 25 presser 68 and wherein the resistance of the spring 64 to the rearward movement of the wiper causes the latter to move forwardly from the work simultaneously driving the wiper 66 up the heel edge of the carrier 60 and wherein the forward movement of the wiper in a path inclined forwardly toward the work. It will be obvious this feature facilitates the production of a well defined edge at the rear of the shoe. 30 Before the end of the forward movement of the wiper and preferably before the wiper has reached the point in its movement to which it tends to draw the upper over the edge of the last, the heel driver bar drives a tack 90 into the rear heel of the last. The upper is thus held at the rear end of the last while the wiper completes its forward movement, and will upwardly draw closely against the last between the lower 35 tack and the point where the upper tack is driven into the innersole. Preferably also the end tack is driven after the wiper has advanced part way in its forward movement. This is particularly desirable where 40 morticed counters are used, since the flanges of such counters are pressed into close relation to the innersole by the wiper and it is desirable that the upper and counter be not secured to the last until the counter has 45 been pressed down into its proper position.

46 The presser 66 engages the rear of the upper near the innersole preferably just before the end of the forward movement of the carrier. The presser forces the upper 50 and the counter closely against the last at

the rear adjacent to the sole, and cooperates with the wiper to form a well defined edge at the rear of the upper. The acting face of the presser is arranged so that as it strikes the work it will rest evenly against the rear face of the last and thus force the upper and counter into close relation to the rear of the last adjacent to the last bottom.

55 It will be seen that the presser imparts an impulse to the last in a forward direction. The corrugated lower face of the stop 26 against which the last is held tends to prevent forward movement of the innersole, and consequently the impulse of the presser moves the last and innersole relatively to so shift the innersole rearwardly upon the last. Where the innersole is tacked to the last, still if any rearward movement of the innersole upon the last is permitted, but where the innersole is held upon the last this feature is particularly advantageous in shifting the innersole rearwardly in case it has been overtaken by the operator too far forward. Thus the innersole is held securely against the counter, so as to facilitate the forward movement of the innersole.

60 After the heel of the last or shoe has been driven into secured relation, as shown in FIG. 1, and while they are held in such relation, consideration is automatically given to the rear end of the shoe to drive a tack 95 through an orifice in the wiper. Preferably, approximately the end of the wiper 66 is engaged of the carrier. The carrier 60 is arranged upon the carrier a predetermined distance forwardly of the presser 68, and as the presser has been brought against the heel of the last before the tack is driven by the driver bar 95, it will be seen that the presser acts as a gage to control the position at which the tack is driven. It will be obvious the adjustment permitted the presser allows the tack to be driven at a greater or less distance from the edge of the last. The tack is preferably driven through the upper, the counter and the innersole and is clenched upon the heel plate of the last. It would be within the present invention to insert simultaneously a plurality of tacks, for example upon opposite sides of a rear seam. After the upper tack is driven, the heel pin is automatically depressed, the other automatic parts of the machine assume their initial position and the last may be removed from the machine. If desired a plurality of tacks may be successively inserted in the end and in the sole of the shoe by successive depressions of the treadle while the last remains in position.

65 Since the end of the last may be moved laterally by moving the last upon its pivot, said tacks may be spaced laterally from each other by shifting the last slightly between successive operations.

The devices acting upon the work at the heel and more particularly the wiper and presser tend to spread apart and move the ends of the counter downwardly toward the cone of the last. This is objectionable on account of the necessity of bringing the counter ends back into position before lasting. It is particularly disadvantageous where a flanged counter is used since, if the corners of such counters are depressed below the edge of the innersole, they cannot be brought back into position by the laster except at the expense of some trouble. It will be borne in mind that the flanged or molded counters are quite stiff and if the flanges of such counters are caught at their ends, below the side edge of the innersole, they must be manually raised before lasting, in order that the counter may be brought closely against the sides of the last. An important function of the work-engaging members 82 is to prevent the ends of the counter being moved downwardly below the edge of the innersole.

25 The wiper and presser coöperate to bring the upper into close contact with the last and to form a well defined edge at the rear of the heel seat, so that in lasting the operator starts with a heel seat in considerably better shape than is commonly produced in assembling by hand. He is thereby enabled to form better heel seats and also to produce them with less effort.

The machine herein shown and described is claimed in an application filed August 15, 1906, Serial No. 330,705, of which the present application is a division.

Having described my invention, what I claim as new and desire to secure by Letters Patent of the United States is:—

1. The method of assembling parts of boots and shoes which consists in supporting an innersole upon the bottom of a making last, arranging an upper and counter about the last in unsecured relation thereto, holding the ends of the counter against the sides of the last, then pressing the counter against the rear face of the last adjacent its tread face and against the rear edge of the innersole, pressing the counter against the face of the innersole and thereafter securing the counter to the innersole.

2. The method of securing a counter to

an innersole in assembled relation upon a last which consists in holding the ends of the counter against the sides of the last, then pressing the counter against the rear face of the last adjacent to the bottom of the last and pressing the innersole against the counter, and thereafter securing the counter to the innersole.

3. The method of assembling parts of boots and shoes which consists in supporting an innersole upon the bottom of a making last, arranging an upper and counter about the last in unsecured relation thereto, holding the rear of the counter in close relation to the end of the last at a point removed from the sole, pressing the sides of the counter against the sides of the last, thereafter pressing the counter against the rear face of the last at the sole edge and securing the counter to the innersole.

4. The method of assembling parts of boots and shoes which consists in arranging an upper, a molded counter and an innersole in loose relation upon a making last, pressing the flange of the counter against the face of the innersole at the extreme rear of the heel, thereafter securing the counter and upper to the rear face of the last, straining the upper over the rear edge of the last and thereafter securing the upper and counter to the innersole at the extreme rear of the heel.

5. The method of assembling parts of boots and shoes which consists in supporting an innersole upon the bottom of a making last, arranging a lined upper and a counter about the last in unsecured relation thereto, wiping the upper and the ends of the counter forwardly along the sides of the last and holding them, securing the upper and counter to the rear face of the last, wiping the upper and counter over the edge of the last at the rear end thereof, and inserting a fastening through said upper and counter into the innersole.

In testimony whereof I have signed my name to this specification in the presence of two subscribing witnesses.

ORRELL ASHTON.
